UNITED STATES PATENT OFFICE.

EDWARD KRONMAN, OF NEW YORK, N. Y.

DESIGN FOR A COFFEE-URN HOT-WATER JACKET.

SPECIFICATION forming part of Design No. 36,286, dated April 14, 1903.

Application filed January 24, 1903. Serial No. 140,448. Term of patent 7 years.

To all whom it may concern:

Be it known that I, EDWARD KRONMAN, a citizen of the United States, residing at No. 87 Madison street, in the city, county, and State of New York, have invented and produced a new, original, and ornamental Design for Coffee-Urn Hot-Water Jackets, of which the following is a specification, reference being had to the accompanying drawings, forming part thereof.

Figure 1 is a perspective view of a hot-water jacket for coffee-urns, showing my ornamental design. Fig. 2 is a front view, and Fig. 3 an end view, thereof.

As shown in the drawings, the leading or material feature of my design relates to the ornamental configuration of the walls of the water-jacket; and it consists in forming the said walls with externally-convex curves *a* at the mid-height thereof and a concave curve *b* upon each side of said convex curve *a*, said concave curves *b b* blending into and forming continuations with the convex curve *a* in the

center and terminating at their upper and lower extremities in flat surfaces or borders *c c*, the outer faces of said flat surfaces or borders *c c* being in the same vertical plane with each other and with the outermost surface of the convex curve *a*, the curves *b b* being within the line through the outer faces of such flat surfaces and convex curve, giving to the design a most pleasing and ornamental appearance. The end wall is of like contour, and the end and side walls join in a miter, with the flat surfaces *c c*, convex curves *a*, and concave curves *b b* coinciding.

Having thus described my invention, what I claim as new, and desire to secure by Letters Patent, is—

The ornamental design for a hot-water jacket for coffee-urns, as herein shown and described.

EDWARD KRONMAN.
